UNITED STATES PATENT OFFICE

LEWIS J. STERN, OF NEW YORK, N. Y., ASSIGNOR TO STERLING CLOCK CO. INC., A CORPORATION OF NEW YORK

ELECTRICALLY OPERATED CLOCK

Application filed February 8, 1926. Serial No. 26,706.

My invention relates to improvements in electro-magnetic means for "winding" spring motors, such as may be used for operating clock trains or like mechanism.

The objects of this invention include the provision of an arrangement which is very simple and durable for the purposes desired and which is of an inexpensive and compact construction and accurate and efficient in its operation. Further and more specific objects, features and advantages will more clearly appear from the detail description given below taken in connection with the accompanying drawings which form a part of this specification.

In the drawings, Fig. 1 is a face view of a clock embodying my improvements in one form.

Fig. 2 is a side elevational view of the clock parts with portions of the outer casings removed or shown in section.

Fig. 3 is a sectional view of the same clock, this section being taken substantially along line 3—3 of Fig. 2.

Fig. 4 is a further sectional view taken substantially along the line 4—4 of Fig. 2.

Fig. 5 is a top plan view showing the exterior of the same clock.

Fig. 6 is a detail elevational view taken in a direction indicated by the arrows 6—6 of Fig. 3 and also showing a portion of the clock casing in section.

Fig. 7 is a detail view taken in a direction as indicated by the arrows 7—7 of Fig. 3.

Fig. 8 is a detail sectional view taken substantially along the line 8—8 of Fig. 3.

Fig. 9 is an enlarged view showing a portion of Fig. 3.

Referring to the drawings, a clock casing or housing is indicated at 10. This casing may be of a type adapted to be mounted upon the instrument panel or dashboard of an automobile and may comprise a body portion 11 for receiving the electro-magnetic clock and mechanism hereinafter described. The forward portion of the casing 10 may be formed with an outwardly extending flange having its periphery of a shape corresponding to and harmonizing

with the other instruments on the dashboard if desired. This enlarged flange portion may provide a recess 12 within which the clock face plate 13 may be placed with its periphery resting against the flange of the clock casing. A glass cover plate 14 in turn rests against the clock face at its periphery, which glass may be retained in place by a suitable beaded flanged member 15 crimped at 16 over a flanged member 17 which telescopically receives the flanged casing. The flanged member 17 may be retained in position upon the casing by means of screws 18 which are provided with nuts as at 19, the peripheral edges of which protrude through adjacent slots in the flanged member 17 (see Figures 1 and 2).

A suitable clock mechanism of any preferred conventional form may be used and is indicated at 20. This mechanism may be retained within a frame work comprising plates 21 and 22 held in spaced relation by connecting posts as at 23. The plate 21 may be provided with a suitable flanged recess for receiving the clock mechanism, such mechanism being retained in the recess by screws as at 24.

The electro-magnetic operating mechanism hereinafter described is mounted at the front and rear faces of the plate 22. The parts mounted upon the front face as shown in Fig. 4 will be first described. The main clock arbor 25 is provided with a ratchet wheel 26 adjacent the plate 22. For operating a clock of the type indicated, this ratchet wheel may be provided with 60 ratchet teeth corresponding to the 60 minutes of an hour and designed to permit the ratchet wheel to be advanced through an angle represented by one tooth each minute so that the wheel makes one complete revolution per hour. Turning force is continually exerted against the ratchet wheel by means of a pawl 27 which is urged into contact with the ratchet teeth by a spiral spring 28. This spring comprises what may be termed the "main spring". The mechanism now being described may be termed a "spring motor" and it will be understood that when reference is made to the spring 100

as being "wound", this is intended to mean that the spring is under tension. When the spring motor is referred to as being "unwound", the spring 28 will also be under tension but will be contracted to a considerable extent as compared with its length when "wound".

The pawl 27 may be pivotally mounted at 29 at one end of a bell crank member 30, which in turn is pivoted at 31. The pawl member 27 may be stamped from sheet metal into the form of a rigid channel member as indicated in Fig. 4 having a pair of perforated lugs at 32 for pivotal engagement 15 with the bell crank member 30. A hook portion 33 may also be struck up from the channel member for engagement with the spring 28. The opposite end of the spring 28 may be made fast in respect to the frame parts 20 in any desired manner. As here shown, however, provision is made for adjusting the tension of the spring 28 by providing a pin 34 passing through a slot 35 in the plate 22 and being adjustable within said slot in 25 a direction longitudinally of the spring. (See Figs. 3, 6 and 7.) Suitable clamping nuts as at 36 are provided for securing the pin at the desired position along the slot 35. The slot 35 may be formed with its 30 edges struck down as indicated at 37 to provide a channelway for receiving one of the clamping nuts and for retaining the nut against rotation.

The bell crank member 30 may be formed 35 with an arm 38 adapted to be engaged by an armature portion 39 hereinafter described. The arm 38 may also be provided with a switch operating finger 40 hereinafter referred to.

40 The parts mounted upon the rear face of the plate 22 will now be described. An electro-magnet 41 is provided with a suitable winding having electrical characteristics depending upon the character of the 45 electrical source of supply with which the device is intended to be used. This electro-magnet may be secured as by a screw 42 to a pole piece and supporting member 43, which in turn may be riveted as indicated 50 at 44 (see Fig. 6) to the plate 22. The magnet core is held firmly against an end portion 44' of the pole piece 43 by the screw 42. From the portion 44' the pole piece is extended as at 45 longitudinally of the electro-magnet and terminates in a pole face 46, which may be substantially in alignment 55 with a pole face 47 at the end of the magnet core opposite from the screw 42. The cross-sectional dimensions of the pole piece 43 may be effectively increased, particularly for a purpose hereinafter referred to, by a supplemental member 47' formed of magnetic material. The terminals of the winding of the electro-magnet 41 may be respec-

tively attached to a terminal post 48 and a binding post 49.

The terminal post 48 is suitably insulated from the plate 22 by conventional insulation washers and is provided with a contact 70 piece 50 of silver or other good contact making material and is designed to cooperate with a spring contact arm 51 which is electrically connected to the framework and thereby grounded for the return circuit. 75 The contact piece 50 may be held in place upon the terminal post 48 by a suitable nut 52. The binding post 49 is also insulated from the plate 22 by conventional insulation washers and as here shown (see Fig. 6) is 80 provided with a novel form of means for attaching a conductor thereto. It has been found to be desirable to introduce the conductor for carrying current to the magnet into the clock casing in a direction perpendicular to the plate 22 and to provide an attachment for such conductor whereby the conductor needs only to be rotated for detachment or to secure the same in position. The binding post hereinafter described has 85 been found to fulfill these requirements in a simple and dependable manner. Referring again to Fig. 6, a binding screw 53 extends through the plate 22 in a direction from the front to the rear and is provided with a nut 54 for securing the same in position within the insulation washers 55. The end of the magnet wire 56 may be provided with a suitable terminal washer or may be wrapped around the screw 53 and held in such position by terminal member 57. This terminal member as shown is formed with an axial threaded aperture for receiving the screw 53 and at its opposite end is suitably recessed for receiving the end of a connecting wire 100 58. This recessed end of the terminal member may be suitably crimped or soldered to the end of the connecting wire. With this form of construction the connecting wire 58, which if desired may be of a relatively large 105 size, may be introduced straight into the clock casing from the rear without bends or kinks which might interfere with the more delicate parts of the mechanism. After insertion, the wire 58 may be turned or twisted axially in order to bring its terminal member into firm engagement with the magnet wire. With this form of conductor attaching means, the electrical connection may be very readily inserted and attached without disturbing the clock or taking it out of its casing.

An armature 59 cooperates with the pole faces 46 and 47 and is formed with the extension 39 above referred to (see Figures 4 and 8). A pair of armature supporting posts 60 and 61 extend upwardly from the plate 22 and are surmounted by a plate 62 within which a bearing 63 is provided for a rotatable post 64. The armature 59 is

rotatably mounted upon this post by means of a member 65 riveted as at 66 to the armature and provided with suitable struck-up apertured lugs 67 for receiving the post 64. 5 A coil spring 68 surrounds the post 64 and has one end bearing against the supporting post 60 and its other end bearing against the armature member to normally hold the armature in spaced relation from the pole faces. 10 The post 64 forms an extension of the pivoting means for the bell crank member 30, as above referred to, and designated by the numeral 31.

It will be noted that the spring 68 serves 15 to retract the armature 59 from the pole faces independently of the action of the main power spring 28. Accordingly, when the armature 59 is attracted to the pole faces upon energization of the electro-magnet, the 20 armature during the first part of its movement is relatively free to acquire a substantial momentum before the armature extension 39 comes into engagement with the bell crank arm 38. Upon engagement of the extension 39 with the arm 38, the bell crank is 25 turned in a manner to draw the pawl 27 along the ratchet wheel 26 for a distance amounting to the space between two teeth. At the same time the main power spring 30 30 28 will be "wound" or placed under greater tension. As soon as this action is accomplished, a switch mechanism hereinafter described will effect an opening of the circuit of the electro-magnet thus permitting the 35 armature to be retracted by the spring 68 and leaving the bell crank 30 and pawl 27 to be gradually drawn around by the spring 28 in a direction to rotate the ratchet wheel 26. It will be noted that the spring 68 is 40 of relatively light construction and is not of sufficient strength to prevent the armature from acquiring substantial momentum during the first part of its movement. The effective motive force of the magnet is materially augmented by reason of this momentum and accordingly during the latter part of the movement of the armature a power spring of considerable strength may be "wound" 45 by the use of a magnet of relatively small dimensions. This permits of a more compact construction than has heretofore been achieved with devices of this character. Furthermore, with this construction the power spring may be fully tensioned or 50 "wound" during a very short interval of time. This permits of a clock construction of greater accuracy and dependability. Also, the operation of the main spring is not interfered with by any residual magnetism 55 of the electro-magnet since when the magnet is de-energized the armature is disconnected from the bell crank 30 so that any tendency of the residual magnetism to pull on the armature does not oppose the main 60 spring 28. The armature does not act upon

the main spring except when the magnet is fully energized.

Attention is also directed to the magnetic circuit of the electro-magnet which comprises not only the core but also the pole piece 43 above described, the armature 59 and the pole faces 46 and 47. Although but a single electro-magnet coil is used, it will be noted that the magnetic circuit will be very nearly closed and hence particularly effective just as the greatest load occurs during the "winding" of the main power spring. 75

The switch for controlling the current to the electro-magnet will now be described, reference being had particularly to Figures 80 3 and 9. The circuit to the electro-magnet is made or broken by the cooperating contacts 50 and 51 above referred to. The contact 50 is stationary, whereas the spring contact member or arm 51 may be riveted 85 as at 69 to a pivoted support 70 which is secured to a shaft 71. The shaft 71 is received by a bearing bracket 72 fastened to the plate 22 as by screw 73. The lower end of the shaft is received in a bearing 74 90 formed in the plate 22 (see Fig. 7). A spiral spring 75 surrounds the shaft 71 between the bearing bracket 72 and the rotatable support 70 and serves to normally bias the spring contact arm 51 and its support 95 toward the open circuit position. To effect this action the spring may have one end in contact with the bearing bracket 72 as shown and its other end in contact with a struck-up lug 76 formed upon the supporting plate 100 70. The supporting plate may be formed of magnetic material and provided with an integral struck-up armature portion 77 having two faces at angles to each other for cooperating respectively with the rear of 105 pole face member 46 and the auxiliary pole piece 47 above referred to. The supporting plate 70 is further provided with a slot or recess 78 of substantial width. The switch operating finger 40 previously referred to 110 extends upwardly through a suitable aperture in the plate 22 and into the recess 78 and is there adapted to alternately engage the sides of the recess during each cycle of 115 operation of the switch.

The manner of operation of the switch will now be described. When the power spring is substantially "unwound", the switch parts and armature will first be in their relative positions as shown in Fig. 3. 120 The switch operating finger 40 will have come into contact with the outer side wall of the recess 78, thus causing the switch arm 51 to be moved to circuit closing position against the action of the biasing spring 125 75. The magnet will thereupon be energized, causing the armature to be attracted in the manner above outlined. As soon as the armature extension 39 engages the bell crank member 30 the switch operating finger 130

will be drawn away from the side of the recess 78. However, the biasing spring will be unable to again open the switch at this time, since the switch armature 77 will be close to the pole face member 46 and pole piece 47' and in such position the armature 77 provides a magnetic by-pass and is attracted to the pole face and pole piece with sufficient force to withhold the biasing spring 75 from acting. The auxiliary armature 77 also prevents the switch from accidental premature opening as by jarring. However, as the armature 59 approaches the pole faces 46 and 47 and the power spring becomes wound in the manner above described, the switch operating finger 40 will come into contact with the inner side wall of the recess 78. As a result, just as the power spring becomes "wound," the finger 40 will force the supporting plate 70 and its contact 51 to open circuit position, as shown in dotted lines in Fig. 9, since the action of the main armature 59 will be sufficiently powerful to overcome the attractive force on the auxiliary armature 77. As the switch opens, the magnet will become de-energized, thus permitting the main armature to be retracted to normal position. Thereafter, during the succeeding minute 30 the bell crank member 30 and the switch operating finger 40 will gradually move back to the positions indicated in Figures 3 and 4, the main spring driving the clock meanwhile. At the end of the minute this cycle of operation of the switch and armature is repeated.

With the form of switch above described, the various parts are kept under positive control during each part of the cycle of operation. The switch is closed at the appropriate time and is kept closed for energizing the magnet until the power spring is completely wound to the desired extent. Thereupon the switch is positively opened.

45 Suitable securing bolts 79 for the casing may be formed integral therewith if desired. A clock time setting button of conventional construction is shown at 80.

While I have described my improvements 50 in great detail with respect to a preferred form thereof, I do not desire to be limited to such details or form since many changes may be made and the improvements embodied in widely different forms. Hence, 55 I desire to cover all forms coming within the language or scope of any one or more of the appended claims.

What I claim as new and desire to secure by Letters Patent is:

60 1. Spring motor controlling mechanism comprising in combination an electro-magnet with an armature, means operated by said armature for "winding" the spring motor, and a switch operatively associated 65 with the armature for controlling the elec-

tro-magnet, said armature being attracted toward the pole pieces upon energization of the electro-magnet and being relatively free to acquire momentum during the first part of its movement, said spring motor winding means being positioned to be acted upon by said armature only during the latter part of its movement.

2. Spring motor controlling mechanism comprising in combination an electro-magnet with an armature normally spaced a substantial distance from the pole pieces of the electro-magnet, means operated by said armature for "winding" the spring motor, and a switch operatively associated with the armature for controlling the electro-magnet, said armature being attracted toward the pole pieces upon energization of the electro-magnet and spring "winding" means being positioned to be first engaged by said armature during the latter portion of movement whereby the electro-magnetic force in addition to momentum of the armature is then imparted to the spring motor.

3. In an electric clock, the combination 90 with an electro-magnet of an armature therefor, a main spring, means engaged by the armature after its initial movement when attracted by the magnet for "winding" the main spring, said armature being disconnected from and ineffective on said winding means when the magnet is de-energized.

4. In an electric clock, the combination with an electro-magnet of a pivoted armature therefor, a main power spring, and a pivoted lever connected to said spring, said armature being provided with a portion engaging said lever but only after the armature is set in motion by the magnet, such engagement effecting a movement of the 105 lever for "winding" the spring.

5. In an electric clock, the combination 110 with an electro-magnet of an armature pivotally mounted upon a shaft, a main power spring, and a lever connected to said spring and also pivotally mounted upon said shaft, said armature being movable about its mounting independently of said lever and being provided with a portion for striking 115 said lever during the latter part of its movement after the magnet is energized for attracting the armature, such striking effecting a movement of the lever for "winding" the spring.

6. In an electric clock, the combination 120 with an electro-magnet of an armature pivotally mounted upon a shaft, a main power spring, a lever connected to said spring and also pivotally mounted upon said shaft, said armature being movable about its mounting independently of said lever and being provided with a portion for striking 125 said lever during the latter part of its movement after the magnet is energized for attracting the armature, such striking effect-

ing a movement of the lever for "winding" the spring, and a spring for immediately restoring and normally maintaining said armature at a position spaced from the magnet pole pieces.

7. In an electric clock, the combination with an electro-magnet of a resiliently controlled striking armature therefor, a main power spring, a pivotally mounted lever connected to said spring, said armature being provided with a portion for engaging said lever when the magnet is energized for attracting the armature, such engagement effecting a movement of the lever for "winding" the spring, and a switch for controlling the circuit of the magnet, said lever as moved by said armature and said power spring respectively acting to open and close said switch.

20 8. In an electric clock, an electro-magnet winding with a core therein having one end which comprises a pole face, a suitably shaped pole piece secured to the other end of said core and extending longitudinally of the core and terminating in a flat portion forming another pole face in alignment with the first, an armature for cooperating with the pole faces when the magnet is energized for "winding" the clock, a switch in the circuit of the electro-magnet, and an auxiliary switch controlling armature associated therewith forming an increased magnetic path for said suitably shaped pole piece.

35 In testimony whereof I have signed my name to this specification.

LEWIS J. STERN.
